RECLINING CHAIR WITH MOVABLE HEADREST

Albert M. Spound, Wellesley Hills, Mass.

Application September 30, 1959, Serial No. 57,735

Term of patent 14 years

(Cl. D15—1)

Fig. 1 is a front elevational view of a reclining chair with movable headrest showing my new design;

Fig. 2 is a side elevational view;

Fig. 3 is a rear elevational view;

Figure 4 is a fragmentary plan view of the chair taken in the direction of the arrow 4 of Figure 2;

Fig. 5 is a side elevational view showing the chair in reclining position;

Fig. 6 is a rear elevational view thereof; and

Figure 7 is a fragmentary front elevational view of the chair taken in the direction of the arrow 7 of Figure 5 and showing the headrest in greater detail.

I claim:

The ornamental design for a reclining chair with movable headrest, as shown.
